BY *Franklin Scott, ATT'Y.*

UNITED STATES PATENT OFFICE.

FRANK LASHER, OF BENNINGTON, VERMONT, ASSIGNOR TO THE LASHER STOCKING COMPANY, OF SAME PLACE.

STITCH-HOLDING MECHANISM FOR KNITTING-MACHINES.

SPECIFICATION forming part of Letters Patent No. 481,631, dated August 30, 1892.

Application filed August 21, 1888. Serial No. 283,351. (No model.)

To all whom it may concern:

Be it known that I, FRANK LASHER, of the town of Bennington, in the county of Bennington, and State of Vermont, have invented 5 certain Improvements in Stitch-Holding Mechanisms for Knitting-Machines, of which the following description, in connection with the accompanying two sheets of drawings, constitutes a specification.

10 The subject-matter of this invention is applicable to rotary machines for tubular knitting, and some features thereof are equally applicable to stitch-holders used on machines for straight knitting. It embraces improvements 15 in the stitch-holding blades themselves at the points where they take the yarn between the needles, and also relates to a special form of the stitch-holder blade and mode of pivoting the same so that it may be worked 20 by oscillation and may be individually inserted in or removed from the machine without disturbing the pivot of oscillation or any of the adjacent parts, together with special appliances for operating such blades when 25 in use.

My invention is fully shown in the accompanying sheets of drawings as applied to a small rotary machine for knitting a tubular fabric like a cuff or a stocking-leg, in which 30 the finished product passes down into or through the interior of the knitting-cylinder.

Figure 1 is a partial plan view of the top of a needle-cylinder, showing my improved stitch-holders and one of the cam-plates for 35 operating them in one direction in position. Fig. 2 is a vertical diametrical section taken on the plane of the line 1 2 of Fig. 1, and shows one of the stitch-holders in elevation. Fig. 3 is a plan view of a partial transverse 40 section through the cylinder, taken on the line 5 6 of Fig. 4, and shows the two lower cam-plates in position. Fig. 4 shows a vertical section taken on the plane of line 3 4 of Fig. 3 of the cylinder cam-plate and socket 45 in which it is adjusted. Fig. 5 is a top plan view which shows the relative positions of the stitch-holder and needles and the yarn with which they are supplied. Fig. 6 shows a rear view of the needles and of the front 50 section of the stitch-holder points, showing position of the yarn and stitches. Figs. 7

and 8 are respectively a plan and cross-sectional view of the fulcrumed hoop upon which the oscillating stitch-holders are pivoted. Fig. 9 is a face view of that section of the 55 needles opposite the feed-thread, showing the position assumed by the thread as it is paid in, and also the position of the needles at the same time.

The first part of my invention relates to the 60 peculiar construction of that part of the stitch-holding blade which supports the yarn between the needles, whereby means are provided for preventing the upward stroke of the needles from splitting or damaging the stitch 65 supported by said blades and their downstroke from shearing them off, and whereby extra space is provided for the yarn between the blades. This is accomplished by milling down both sides of the yarn-supporting part of the 70 stitch-holding part of the blade, so as to leave a thin standing web, which carries the stitch, flanked on each side along its under edge abreast of the needles by a thicker rib, which 75 fends off the needles from damaging interference with the yarn on the stitch-holders.

Another part of my invention relates to special provisions for pivoting the stitch-holders by means of open notches cut in one of their edges upon a fulcrum-ring or upon a 80 circumferential series of pivots, which surrounds or surround the needle-cylinder, in connection with a pair of cams or analogous devices arranged one above and one below the plane of the pivot of oscillation for the 85 purpose of imparting to said stitch-holders their appropriate movements.

The improvement first mentioned is shown in Figs. 2 and 5. In Fig. 2 the stitch-holder is shown at H. It is of thin metallic plate of 90 figure 7 shape. The lower limb is notched on its inner edge, so as to turn or oscillate on a pivot B'. The upper member is milled down from the top to the line x' x', so as to leave a thin standing web r, which is notched at o to 95 catch onto the last thread or onto the edge of the fabric, as hereinafter described.

Several advantages result from this mode of construction. A thicker plate can be employed in making the stitch-holders than could 100 otherwise be used on fine gages, thereby rendering them more durable and less liable to

break. With stitch-holders of ordinary thickness made in this way great freedom for the yarn between them and the needles is obtained and the liability of the thread being broken by knots in the same or bunches thereon getting caught between the needles and stitch-holders is greatly diminished.

The second part of my invention is shown as applied to a rotary needle-cylinder adapted to knitting a tubular fabric. This cylinder is shown in longitudinal section in Figs. 2 and 4 at A. It is longitudinally grooved, as seen at $t\ t$, for the needles N, which are moved vertically by means of a stationary cam-race u , through which the shanks v of the needles travel. Cylinder A has a circumferential groove cut in its external surface a short distance from the top and across the needle-grooves, into which two elastic spring-bands L are sprung. These bands consist each of a coil of fine spring-wire having its two ends united by a screw-plug coupling, so as to form an annular elastic spring. When in position, they just fill the groove around the cylinder and lie close to the needles, leaving barely space for free vertical play of the same.

Above the spring-bands and at the top of the cylinder is fitted a pivot-band B. This is secured firmly to the cylinder. It is transversely grooved with the same number of slots as the cylinder, as shown at $t''\ t''$, Fig. 7, and it also has a circumferential groove g' running around its outer edge, in which is firmly secured the pivot-ring B'. The transverse slots are of a width to receive the stitch-holders H and allow them to freely turn therein. The ring B' constitutes a fulcrum where it crosses each slot $t''\ t''$, across or upon which the stitch-holder H oscillates. The stitch-holders are notched, as shown on their inner edges, so as to maintain proper position and play or oscillate upon the pivot-ring. These open notches possess special advantages over the ordinary construction of a hole and pivot, as the open feature permits their easy detachment or removal from the machine without disturbing the fulcrum or pivot-ring on which they oscillate. Thus any stitch-holder may be removed without disturbing the others or its fulcrum-bearing. When all the holders are in position, they are confined by the spring-band D, which is similar in construction to the bands L L. The pivot-band B is placed vertically at such an elevation as will permit the top of the stitch-holder to play freely over but in close proximity to the top edge of the needle-cylinder.

The table of the machine is seen at J, Fig. 4, and is perforated with a circular opening, in which the needle-cylinder is concentrically adjusted and revolves. In this opening a ring F is fitted and its upper and interior edge forms a concentric back-stop for the stitch-holders to fall back against when their position is not controlled by the cam-plates T T or E.

The relative positions of the needles and stitch-holders are shown in plan in Figs. 1 and 5 and in elevation in Figs. 2, 4, and 9. The movements of the stitch-holders are controlled by the upper cam-plate E and the under cam-plates T T. Two of the latter are provided to facilitate reciprocal knitting.

In the machine illustrated the cylinder may have motion in either or both directions. In practice when the heel of the stitch-holder strikes the bevel of cam T it is forced inwardly and the blade part r is thrown outwardly or partially withdrawn from under the stitch and so that the point o shall be drawn back behind the range of needles and out from under the last stitch which is dropped onto the inner and lower part of blade r . As the cylinder revolves when the heel of the holder passes off point $e\ e$ of plate T, the upper part or head of the holder marked n engages bevel h of plate E, and in passing it is crowded inwardly between the needles. In doing this the point o forces the last-formed series of stitches into the position shown in Fig. 5. This position of the blades causes the thread of the last-formed row of stitches to be drawn snugly around the stems of the needles in such way that when the needle commences to ascend preparatory to receiving a new feed the latch will unavoidably be opened and the web of the fabric will be held back free and clear of the needles while the needle is descending, as from h' to h in Fig. 9, and is then forming a new series of stitches. The web of the fabric as made is, by the reciprocating action of the stitch-holder blades, worked off the inner end of the blades $r\ r$ and is delivered into the interior of the needle-cylinder.

In this machine no weight or take-up device is essential to connect with the fabric to effect its proper withdrawal from the knitting devices.

The needles when broken may be removed by springing out the bands L L and pulling the needles from underneath. The stitch-holders H may in like manner be exchanged by springing out the band D, which permits them to be easily withdrawn.

Cam-plates T T may be circumferentially adjusted with reference to the cylinder by means of bolts W W and elongated slots $c\ c$ in plate V, and longitudinally by means of slot d and screws Y Y.

Hence I claim as my invention—

1. An oscillating stitch-holder provided with a thin standing web over which the yarn as it reaches from needle to needle is stretched, standing upon a base thicker than said web, so as to have a projecting rib or guard on each side of the web as a provision for fending off the needles from contact with the sides of the web and also provided with a hook or notch on or in the upper edge of said web, and an open notch in one edge of the body of the same for the reception of the fulcrum-pivot, in combination with a stationary ful-

erum-pivot and means, substantially as shown, for holding said stitch-holder and pivot in proper working engagement, substantially as and for the purposes specified.

5 2. The combination, with a rotary knitting-needle cylinder having a series of longitudinal slots or ways, of a series of needles working in said ways, a fulcrum-ring surrounding said cylinder, a series of stitch-holders of substantially the form described provided with open pivot-notches and pivoted so as to oscillate upon said fulcrum-ring and in radial planes between the needles, said stitch-holders having provisions, substantially as shown, 15 for engaging the last-formed range of stitches and sinking them inwardly during the process of introducing a new feed-thread, and cams for actuating them arranged to operate substantially in the manner described, and 20 for the purposes set forth.

3. In combination with a needle-cylinder, of a series of needles arranged to work in longitudinal grooves upon said cylinder, a series of fulcrum-pivots surrounding said cylinder, 25 a series of stitch-holders having open pivot-notches to oscillate upon said fulcrum-pivots between said needles, and a pair of cam-plates arranged one above and the other below the pivot of oscillation for imparting to said 30 stitch-holders their proper oscillating movements by impact therewith during the revolution of the needle-cylinder, substantially in the manner described, and for the purposes set forth.

35 4. The combination, substantially as shown,

of the needle-cylinder, needles, stitch-holders, concentric fulcrum-pivot ring slotted for the stitch-holders, and the spring-band for retaining the stitch-holders in place, substantially as specified.

40

5. The combination of the needle-cylinder, needles, and a series of stitch-supporters openly notched on one edge for a fulcrum-bearing and having the described notch or gap to engage the last row of completed 45 stitches and sink the same between the needles pivoted side by side along or upon a fulcrum-bearing, with two cam-faces arranged one above and one below the plane of oscillation and adapted by their construction and 50 connection with said stitch-supporters to impart to the same an oscillatory motion between the needles, substantially as described, and for the purposes set forth.

6. The oscillating stitch-holder provided 55 with the described open fulcrum-notch, in combination with the fulcrum-ring, slotted pivot-band, and retaining-spring band as a means for permitting individual insertion and removal of stitch-holders without disturbing 60 the fulcrum-ring or other pivot which may be provided instead or the adjacent stitch-holders, substantially as specified.

In witness whereof I have hereto subscribed my name, at Bennington, Vermont, this 18th 65 day of August, A. D. 1888.

FRANK LASHER.

In presence of—

FRANKLIN SCOTT,
D. L. BATES.
